UNITED STATES PATENT OFFICE

162,890

WALL LAMP

Eugene Schwarz, Alexander, Ind.

Application October 13, 1950, Serial No. 12,551

Term of patent 14 years

(Cl. D48—4)

To all whom it may concern:

Be it known that I, Eugene Schwartz, a citizen of the United States, residing at Alexandria, county of Madison, and State of Indiana, have invented a new, original, and ornamental Design for a Wall Lamp, of which the following is a specification, reference being had to the accompanying drawings, forming a part thereof, in which—

Fig. 1 is a top plan view of a wall lamp showing my new design;

Fig. 2 is a side elevational view thereof;

Fig. 3 is a front elevational view thereof;

Fig. 4 is an elevational view of the other side thereof;

Fig. 5 is a bottom plan view thereof.

In the wall lamp of my new design, the drawings of the design have been shaded to show a preferred form of contrasting colors.

I claim:

The ornamental design for a wall lamp, as shown and described.

EUGENE SCHWARTZ.
